UNITED STATES PATENT OFFICE.

JAMES OFFINEER, OF ASHLAND, OHIO, ASSIGNOR, BY MESNE ASSIGNMENTS,
TO HIRAM HOLT & CO., OF FARMINGTON, MAINE.

HAY-KNIFE.

SPECIFICATION forming part of Reissued Letters Patent No. 9,335, dated August 3, 1880.

Original No. 82,152, dated September 15, 1868. Application for reissue filed June 11, 1880.

To all whom it may concern:

Be it known that I, JAMES OFFINEER, of Ashland, in the county of Ashland and State of Ohio, have invented a new and useful Improvement in Hay-Knives, of which the following is a specification.

Figure 1 is a perspective view of said knife. Fig. 2 is a side view.

Similar letters of reference indicate corresponding parts.

H is a strip or rod of iron, of suitable length and proper thickness, to which are connected two handles, E and F. At one end of the strip H is attached a two-edged lance-like pointed knife, A, and to the side of the strip are attached three sharp knives, B C D, one above the other, which knives are in shape isosceles triangles, and form saw-teeth upon the strip or bar. The middle knife, C, is longer than the bottom one, 20 and the upper one, D, still longer.

At the upper end of rod H two handles, E F, are attached, and the rod is formed with a crook at the handle F, so that both handles offset from the plane of the cutting-blades, 25 and the upper hand of the operator will be

prevented from rubbing against the hay or straw when the knife is in use.

In operating the knife the lance-pointed knife A will cut both ways, thus opening the way for the easy entrance of the rod H, while 30 by the sawing-like action of the knives B C D they cut rapidly and with great ease.

Having thus described my invention, I claim as new and desire to secure by Letters Patent—

1. The combination, with the bar H, of the end knife, A, and one or more saw-teeth sharpened on their edges, the end knife being placed in line with and the saw-tooth or saw-teeth at right angles to said bar, as and for the purpose 40 specified.

2. In hay-knives, two or more angular knives arranged at right angles to the side of handle-bar H, and successively longer as they are farther removed from the point or end knife of 45 the handle, to operate as specified.

JAMES OFFINEER.
